SHEET RACK FOR PRESSES

Fred S. English and Robert H. Dodds, New London, Conn., assignors to The Babcock Printing Press Manufacturing Company, a corporation of Connecticut

Application October 5, 1926. Serial No. 139,615

34 Claims. (Cl. 271—73)

Our invention relates to a device for temporarily receiving and holding the sheets delivered from a press while the latter is in operation and during the period when the large or main stack of sheets is being removed from the press. Our invention is adapted for use in connection with printing presses, cutting and creasing presses, and other forms of machines from which sheets of stock are delivered into a pile. We have chosen to illustrate our invention as applied to a cutting and creasing press having the well known type of Babcock delivery device and also what is generally called an extended delivery table; that is, a lowering pile table set off at the end of the press and arranged upon a more or less separate framework for receiving a large stack of sheets as they are delivered from time to time from the press. In the operation of presses, especially printing and cutting and creasing presses, considerable time is consumed in removing the stack of sheets which accumulate in the form of a pile, and unless provision is made for receiving the sheets while the pile is being removed and a new pile table placed into position, the press would have to be stopped. As this operation is repeated a number of times during the day, especially where heavy cardboard stock is being delivered, it is desirable to provide means for temporarily receiving the sheets while the main pile is being removed, and the new pile table placed into position. The object of the present invention is to provide a simple and efficient means for receiving the sheets temporarily during the removal of the main stack. One object of the invention is to provide a form of rack which may be extended more or less, according to adjustment, to receive sheets of different sizes. Another object is to provide a folding rack which will be suitable for receiving sheets of large size and at the same time requiring no additional floor space over that required for the extended delivery device itself. Another object is to provide a sheet rack having rolling members which will withdraw from the temporary stack of sheets by a rolling action, thereby transferring the sheets from the temporary rack to the main pile table while the press is in operation, and with the least disturbance to the sheets, and with a minimum effort. This rolling action, as distinguished from a sliding action, we believe to be broadly new. Another object of our invention is to provide a rack which will be suitable for receiving heavy sheets and which will not bind when being moved into and out of operative position. With these and other objects in view

which will be pointed out in the detailed description, the invention in the preferred form is illustrated in the drawings, in which

Figure 1 is a side elevation of the delivery end of a cutting and creasing press having an extended delivery table set off from the end thereof, and to which our invention is applied, 60

Figure 2 is a front elevation of the same taken from the left hand end of Figure 1, 65

Figure 3 is a plan view of the same, 65

Figure 4 is a detail view showing a side elevation of the sheet rack in position, receiving the sheets delivered from the press with a new or unloaded pile table positioned to receive the sheets from the rack, 70

Figure 5 is a similar view showing the sheet rack in the process of being withdrawn to allow the sheets thereon to come upon the pile table, 75

Figure 6 is a similar view showing the rack folded or retracted out of position to allow the sheets to follow upon the main pile on the pile table, 80

Figure 7 is a side elevation on a larger scale showing parts of the device which appear in Figure 1, and 80

Figure 8 is a sectional view showing the details of one of the sliding brackets, 85

In the drawings the numeral 1 represents the front end of the frame of the press which, as aforesaid, may be a printing or cutting and creasing press; and mounted upon this frame is the bracket 2 which supports one end of the extended delivery frame. The side rails 3 which are supported at one end upon the brackets 2 form the upper longitudinal members of the extended delivery frame, and the opposite ends rest upon posts or front legs 5, the lower ends of which are provided with feet 6 resting upon the floor. It will be understood that the bracket 2 is duplicated at opposite sides of the press and likewise the rails 3, legs 5, and feet 6 are also duplicated at opposite sides of the press. Arranged between the end of the press and the forward legs 5 there is a pile table 16 which moves from a position just below the sheet rack to a point adjacent the floor, and it will be understood that this table, which is usually supported upon cables or chains, is adapted to be gradually lowered, step by step, in order to maintain the top of the pile of sheets on this table at a uniform level. Any mechanism may be employed for operating the pile table and as the same are well known in the art, a detailed description thereof is unnecessary in the present case. Reference may be had to the patent of Fred S. English, No. 1,523,869, 105 110

dated January 20, 1925, as showing one form of mechanism for raising and lowering the pile table. When the pile table 16 has received a stack of sheets 15 to the limit of its capacity, as 5 determined either by the weight of the stock, or the table reaching a point near the floor, it is necessary, if the press is to be kept in operation, to provide means for receiving the sheets delivered while the table 16 and pile 15 are being 10 removed, and a new table placed into position, and the present invention is adapted to perform this function.

In the drawings we have shown tapes 10 which are the ordinary delivery tapes on the delivery 15 carriage of a press, and they engage around a front roller 7, a roller 8, and a roller 9, the latter being stationary, while the rollers 7 and 8 reciprocate with the carriage. As the delivery carriage, tapes and rollers are all devices well 20 known in the art, a detailed description is unnecessary in the present case. It is sufficient to point out that the sheets from the press are carried forward on the upper runs of the tapes 10 until the roller 7 reaches approximately the 25 position shown in Figure 1, and upon the return stroke or the movement to the right of the roller 7, the tapes 10 peel off under the sheet allowing it to fall upon the stack which is forming upon the pile table 16, or upon the improved rack to 30 be hereinafter described. The delivery carriage is supported through the wheels 11 upon the carriage tracks 12 arranged at opposite sides of the extended delivery device, in well known manner.

There is a rod 14 extending crosswise on the 35 delivery frame, and it supports the front stops 13 in position for the leading edge of the sheet to strike against in order to cause the sheets to fall into uniform position, and it is common to use similar stops for the rear and side edges of the 40 sheet, but these are omitted for simplicity of illustration.

We have shown at 17 side rods arranged at opposite sides of the extended delivery frame and out of the path of the sheet. As most of the 45 parts of the device are duplicated at opposite sides of the press a description of the parts at one side will suffice for both. One end of the rod 17 is fixed in the bracket 18 which is attached to the carriage track 12. The other end 50 of the rod is secured to the bracket 19 which is attached to the frame of the extended delivery device, the brackets 19 at opposite sides of the machine being connected with a tie rod 20. There is a bracket 22 slidably mounted upon 55 each rod 17 and there are additional brackets 23 slidably mounted on each of these rods, the brackets 22 and 23 performing similar functions. Each of the brackets 22 and 23 carries a roller 24 extending from one side of the machine to 60 the other and there are sufficient of these rollers to support the temporary stack of sheets delivered from the press during the interval required for the change of the delivery table. In order that these rollers 24 may revolve freely, they 65 are mounted in the several brackets 22, 23 by means of roller or ball bearings 25. In Figure 1 we have shown the several brackets which carry the rollers 24 extended to their extreme positions for receiving sheets of maximum size from the 70 delivery device of the press. In Figure 6 these several brackets are shown in their extreme retracted position with the rollers 24 outside of or beyond the path of the sheets to permit the latter to fall on the pile table 16. In Figure 5 75 we have shown the rack partially folded and in

the operation of being withdrawn from the temporary pile of sheets.

On each of the rods 17 there is a bracket 26 fixed in position and carrying an idler sprocket 27. There is a shaft 28 journaled in the brackets 19 and at each end it has attached to it a sprocket 29 arranged in the same plane with the sprocket 27. There is an endless chain 30 which travels around the sprockets 27 and 29 and the chain is attached by means of a pin 31 to the bracket 22, the construction being duplicated at opposite sides of the machine. The shaft 28 is adapted to be manually operated by means of the hand crank 34 which is attached to the end of the shaft 36, the latter being journaled in one of the brackets 19 and in the bracket 37. On this shaft 36 there is a gear 33 which meshes with the gear 32 on the shaft 28. It will be apparent that by turning the crank 34 the motion will be transmitted to the shaft 28 and the sprockets 29 on 95 this shaft will cause the upper run of the chain 30 to move either to the right or left.

The several brackets 22 and 23 which slide on the rods 17 are connected with each other by flexible connections such as chains 38, and 100 one end of this flexible connection is secured to the framework of the machine, such as by the pin 39, as shown in Figure 7. There is a collar 40 adjustably fixed to each rod 17 and this limits the movement of the bracket 22 in one direction, 105 and these collars will be adjusted according to the size of sheet which is to be delivered from the press.

We have provided a set of endless tapes 41 which engage over the shaft 21 and also over the 110 back roller 24 which is carried by the brackets 22 and the under runs of these tapes pass over the idler pulley 42, thence downwardly and around a pin of the weight 43, and thence upwardly to the shaft 21. The purpose of the weight 43 is 115 to keep the tapes 41 taut in any position of the foremost roller 24 around which the tapes engage. These tapes 41 have their upper runs raised sufficiently to extend above the bottom edges of the front stop 13 and serve to prevent the forward 120 edge of the delivered sheet from passing under the front stop 13 in the event that one of the rollers 24 is not in position to properly receive this forward edge of the sheet. Without these 125 tapes the forward edge of the sheet might pass below the front stops 13 and fail to deliver upon the rollers 24. These tapes 41 constitute collectively a curtain for temporarily supporting a plurality of sheets independently of the pile 130 table.

Operation

With the device in the position shown in Figure 6 the sheets are delivered from the delivery device of the press upon the pile table 16 to form 135 the stack 15 and during this operation the rack device is retracted into a position where it will have no effect upon the sheets. At the same time the rack device is folded into compact form for it will not project beyond the extended delivery device, and utilize floor space. When the stack 15 has accumulated to such a point that it has to be removed, the operator, while the press is running, will grasp the hand crank 34 and turn it in the direction necessary for the upper run 140 of the chain 30 to draw the bracket 22 and its roller 24 backwardly or to the right in Figure 6. As this bracket and roller move to the right the upper run of the tapes 41 are extended and this causes the floating weight 43 to rise so 145

that these tapes pass under the delivery device into position to receive the sheets therefrom. As the bracket 22 moves backwardly with its roller the flexible connection 38 is finally straightened out between the bracket 22 and the next bracket 23 and when this occurs the first bracket 23 proceeds to move in spaced relation with the bracket 22. Subsequently, the flexible connection 38 between the first bracket 23 and the succeeding bracket 23 is straightened and thereafter the second bracket 23 continues to move in spaced relation to the bracket 22 and the first bracket 23. This action continues in regard to the successive brackets 23 until the leading bracket 22 stops against the collar 40. If the latter has been positioned in the extreme right hand position for the largest size sheet, then when the bracket 22 comes up against the stop 40 all of the brackets 23 will have been drawn out to their extended position, as shown in Figure 4. If the collar 40 is adjusted to some position to the left of its extreme position, only a part of the brackets 23 will be drawn out to the extended position, and this adjustment may be made when the sheets delivered are of less than the maximum size. If the rack is positioned as shown in Figure 4 the sheets delivered by the delivery device of the press will fall upon the tapes 41 and be supported by these, and by the several rollers 24, and this will continue as long as the rack is in the extended position. The operator may now remove the pile table 16 and the stack of sheets 15 and replace the table 16 by another one, adjusting it to its upper position as shown in Figure 4. By this time a stack of sheets will have accumulated as shown at 15a upon the rack. The operator may now proceed to retract the rack while the press is still in operation and to do so the crank 34 is turned in the opposite direction. The upper run 40 of the member 30 acting through the pin connection 31 will move the bracket 22 to the left in Figures 1 and 4 and the roller 24 carried by the brackets 22 will move with them. As these rollers 24 are freely revolvable on their ball bearings, they 45 will roll from under the stack of sheets 15a instead of sliding and this will permit the stack of sheets 15a to fall gradually upon the new pile table 16 without displacing the stack, except for its transfer from the rack to the pile table. In 50 Figure 5 the rack is shown partially retracted to illustrate the manner in which the temporary stack 15a is transferred to the pile table 16. As the forward brackets 22 come up against the first pair of brackets 23, the section of the chain 55 38 between the brackets falls into a loop and the bracket 22 pushes to the left against the first pair of brackets 23. As the movement of the brackets 22 continues the brackets 23 pick up the remainder of the brackets 23 until the 60 device has been collapsed to the position shown in Figure 6.

It will be apparent that the present device is adapted to be folded into compact form so as not to extend beyond the extended delivery device 65 notwithstanding that it is made to handle very large sheets as well as smaller sheets. The device is also adjustable and adapted to receive different size sheets. There is no disarrangement of the pile of sheets while being transferred from the 70 rack to the pile table and the operation may be performed while the press is in operation, in fact the entire operation of the present device may be carried out without having to stop the press. Owing to the rolling action of the supporting members 24 in the preferred construction as

distinguished from a sliding movement, it is possible to use the device for large or small sheets without disarranging the pile while the rack is being withdrawn.

Having described our invention, what we claim is:

1. The combination with a frame, a pile table thereon and a sheet rack for temporarily receiving the sheets above the table, said rack being movable into and out of sheet receiving position over said table and revolvable sheet supporting members on said rack adapted to disengage from under the sheets by a rolling action. 80
2. The combination with a frame, a pile table thereon and a rack for temporarily receiving sheets above the table, said rack being movable into and out of sheet receiving position over said table and having rollers for supporting the sheets, adapted to disengage from under the sheets by a rolling action. 90
3. The combination with a frame, a pile table thereon, and a rack for temporarily receiving the sheets above the table, said rack being slidable into and out of sheet receiving position over said table, supporting rollers on said rack and tapes 100 engaging over said rollers, whereby the sheets rest on said tapes and rollers, said tapes and rollers being adapted to disengage from under the sheets by a rolling action when the sheet rack is retracted. 105
4. The combination with a frame, a pile table thereon and a rack for temporarily receiving the sheets above the table, said rack including revolvable members for supporting the sheets and adapted to roll from under the sheets piled thereon. 110
5. The combination with a frame, a pile table thereon, and a rack for temporarily receiving the sheets above said table, said rack including revolvable members for supporting the sheets, tapes 115 extending over the tops of said revolvable members, said revolvable members and tapes being adapted to roll from under the sheets piled thereon, said rolling supports being mounted to slide into collapsed or extended position. 120
6. The combination with a frame, a pile table thereon, and a rack for temporarily receiving the sheets above said table, said rack including revolvable members for supporting the sheets, tapes 125 extending over the tops of said revolvable members, said revolvable members and tapes being adapted to roll from under the sheets piled thereon, said revolvable members being mounted to slide into collapsed or extended positions, and means for maintaining said tapes taut over the 130 tops of said revolvable members as the latter are shifted in position.
7. The combination with a frame, a pile table thereon, tracks, members movable along said tracks into extended and collapsed positions, and 135 means carried by said latter members for supporting sheets above said table.
8. The combination with a frame, a pile table thereon, tracks, members movable along said tracks into extended and collapsed positions, and 140 rolling means carried by said latter means and adapted to receive the sheets thereon above the table and adapted to withdraw from said sheets by a rolling action.
9. The combination with a frame, a pile table 145 thereon, tracks, members movable along said tracks into extended and collapsed positions, means carried by said latter members for supporting sheets above said table, means for moving said movable members along said tracks, and 150

adjustable means for limiting the movement of said movable members on said tracks.

10. The combination with a frame, a pile table thereon, tracks, members movable along said 5 tracks, collapsible spacing connections between said latter members, and means carried by said movable members for supporting sheets above said table.

11. The combination with a frame, a pile table 10 thereon, tracks, members movable along said tracks, collapsible spacing connections between said members, and rollers carried by said movable members, for supporting sheets above said table.

12. The combination with a frame, a pile table 15 thereon, tracks, members movable along said tracks, flexible spacing connections between said latter members, rollers carried by said movable members and tapes extending across the tops of said rollers, whereby the rollers and tapes support 20 the sheets when the rack is in extended position.

13. The combination with a frame, a pile table thereon, tracks, members movable along said tracks and adapted to be placed in extended position 25 across the space above said table and to be collapsed into close relation beyond the path of the table, and members carried by said first members, for supporting sheets above the table.

14. The combination with a frame, a pile table 30 thereon, tracks, members slidable along said tracks, flexible spacing connections between the several sliding members, means operating on the endmost sliding member for extending and retracting the sliding members on said tracks, and 35 means carried by said sliding members for supporting sheets above said table.

15. The combination with a frame, a pile table thereon, tracks, members slidable along said tracks, flexible spacing connections between the 40 several sliding members, sprockets adjacent the opposite ends of the frame, a flexible member engaging over said sprockets and connected with the endmost of said sliding members, and means for operating said latter flexible members to ex- 45 tend and collapse said slidable members.

16. The combination with a frame, a pile table thereon, tracks, members slidable on the tracks and having rollers for supporting sheets above said table, flexible connections between said sliding members, tapes engaging over the tops of said rollers and a floating weight for maintaining said tapes taut as said sliding members move on said tracks.

17. The combination with a frame, a pile table 55 thereon and a rack for temporarily receiving sheets above the table, said rack comprising members for supporting the sheets, tracks for guiding said members, on which said members are adapted to be moved into separated position for 60 receiving the sheets and adapted to be moved individually toward each other into collapsed condition, said supporting members, when moved into collapsed condition, being adapted to disengage from the sheets accumulated thereon and 65 to deliver them upon said pile table.

18. The combination with a frame, a pile table thereon, a member slidably mounted over said pile table, sprockets adjacent the opposite ends of the frame, chains extending over said sprockets and connected with the sliding member, and means for operating said chains to move said sliding member backward or forward over said pile table.

19. The combination with a frame, a pile 75 table thereon, a member slidably mounted over

said pile table, revolvable members adjacent the opposite ends of the frame, flexible members extending over said revolvable members and connected with the sliding member and means for operating said revolvable members to move said sliding member backward or forward over said pile table.

20. The combination with a frame, a pile table thereon, a member slidably mounted over said pile table, sprockets mounted on said frame, chains extending over said sprockets and connected with the sliding member, and means for operating said chains for moving said sliding member forward and backward over said pile table.

21. The combination of a press delivery, a pile table and a sheet catcher removably mounted in a plane between said delivery and said pile table, sprockets mounted out of the path of said pile table, chains extending over said sprockets, said chains being connected with said sheet catcher, and means for operating said chains whereby said sheet catcher may be moved into or out of sheet catching position.

22. The combination of a press delivery, a pile table and a sheet catcher removably mounted in a plane between said delivery and said pile table, pulleys mounted out of the path of the pile table, flexible members extending over said pulleys, said flexible members being connected with said sheet catcher, and means for operating said flexible members whereby said sheet catcher may be moved into or out of sheet catching position.

23. The combination of a press delivery, a pile 110 table, and a sheet catcher mounted to slide horizontally in a plane between said delivery and said pile table, tape wheels mounted out of the path of the sheet, tapes extending over said tape wheels and connected with said sheet 115 catcher, sprockets, and chains engaging over said sprockets and arranged out of the path of the sheets and adapted to move said sheet catcher.

24. In a delivery apparatus for sheet-feeding 120 mechanism, a main support comprising a table to receive the sheets discharged from the feeding mechanism, said table being removable from the apparatus to remove the sheets supported thereon, a mechanical auxiliary support adapted to 125 temporarily stop the sheets discharged from said feeding mechanism and to form a complete support for a plurality of sheets, so as to permit removal of the sheets on said table, said auxiliary support comprising an anti-friction device on 130 which the sheets accumulate, said anti-friction device including a roller forming a support for the sheets, and means whereby said auxiliary support is shifted in a line at a right angle to the axis of said roller to drop the sheets from said anti-friction device to the table.

25. In a delivery apparatus for sheet feeding 135 mechanism, a main support to receive the sheets discharged from the feeding mechanism, an auxiliary support adapted to stop the sheets discharged from said feeding mechanism, said auxiliary support being movable into and out of the path of the sheets and adapted to form a complete mechanical support for a plurality of sheets to temporarily prevent delivery to the 140 main support, and means for shifting said auxiliary support, said means including driving members at opposite sides of said auxiliary support co-operating with each other to simultaneously shift both of said sides.

80

85

90

95

150

26. In a delivery apparatus for sheet feeding mechanism, a main support to receive the sheets discharged from the feeding mechanism, said main support comprising a member on which 5 the sheets accumulate, an auxiliary support movable into the path of the material to temporarily prevent delivery to said main support, said auxiliary support including an anti-friction device on which the sheets accumulate so that said 10 auxiliary device forms a complete mechanical support for a plurality of sheets, and means whereby said anti-friction device is withdrawn from said path to drop the accumulated sheets onto the main support, said means including driving members at opposite sides of said auxiliary support cooperating with each other to simultaneously shift both of said sides. 15
27. In a delivery apparatus for sheet-feeding mechanism, a main support comprising a table 20 to receive the sheets discharged from the feeding mechanism, said table being removable from the apparatus to remove the sheets supported thereon, an auxiliary support adapted to temporarily stop the sheets discharged from said feeding mechanism, so as to permit removal of the sheets 25 on said table, said auxiliary support comprising complete mechanical support for a plurality of sheets and including an anti-friction device on which the sheets accumulate, said anti-friction 30 device including a roller forming a support for the sheets, and means whereby said auxiliary support is shifted in a line at a right angle to the axis of said roller to drop the sheets from said anti-friction device to the table, said means including driving members at opposite sides of 35 said auxiliary support cooperating with each other to simultaneously shift both ends of said roller. 40
28. In a delivery apparatus for sheet feeding mechanism, a main support, means for delivering sheet material to said support, and an auxiliary support forming a complete mechanical support for a plurality of sheets, said auxiliary support comprising a curtain movable into and out 45 of the path of the sheets between said means and the main support. 45
29. In a sheet delivery apparatus, a support, means for delivering sheets to said support, a roller movable into or out of the path of the sheets between said means and the support, and 50 a curtain cooperating with said roller for extension into said path to form a complete mechanical auxiliary support for said sheets. 55
30. In a sheet delivery apparatus, a support, a means for delivering sheet material to said support, and a curtain adapted to be rolled into or out of the path of the sheets between said means and said support and adapted to form a complete mechanical support for a plurality of sheets. 80
31. In a sheet delivery apparatus, a support, means for delivering sheets to said support, a roller movable into or out of the path of the sheets between said feeding means and the support, and a curtain cooperating with said roller and adapted to be rolled into said path to form a complete mechanical auxiliary support for a plurality of sheets. 85
32. A sheet support comprising a curtain movable to receive and release the sheets to be supported, said curtain being adapted to be rolled out of engagement with the sheets to be supported, and means for tensionally adjusting said curtain. 90
33. In a delivery apparatus for sheet feeding mechanism a main support to receive the sheets discharged from the feeding mechanism, said main support comprising a member on which the sheets accumulate, a mechanical auxiliary 100 support movable into the path of the sheets to temporarily prevent delivery to said main support and to permit a plurality of sheets to pile thereon whereby said auxiliary support provides a complete support for the sheets, said auxiliary 105 support including an anti-friction device on which the sheets accumulate, and means whereby said anti-friction device is withdrawn from said path to drop the accumulated sheets onto the main support. 110
34. In a delivery apparatus for sheet feeding mechanism, a main support to receive the sheets discharged from the feeding mechanism, said main support comprising a movable table on which the sheets accumulate, a mechanical 115 auxiliary support movable over said table to temporarily prevent delivery of sheets to said table, and adapted to permit a plurality of sheets to pile thereon whereby said auxiliary device provides a complete support for the sheets, said 120 auxiliary support including an anti-friction device on which the sheets accumulate, and means whereby said anti-friction device is withdrawn from said path to drop the accumulated sheets onto said table. 125
